INVENTOR

BY *Victor J. Evans*

ATTORNEY

WITNESS:

A. E. Evans.

UNITED STATES PATENT OFFICE.

MAURICE A. ESTABROOKS, OF AUGUSTA, MAINE.

DOOR HOOK.

Application filed July 25, 1927. Serial No. 208,350.

This invention relates to a latch for a door or other barrier, the general object of the invention being to make the latch extensible so that its hook part can be moved toward 5 and away from the keeper member, and when moved into engagement with the keeper member, the improved latch will tend to hold the barrier tightly closed.

A further object of the invention is to provide a lever for adjusting the hook member of the latch, said lever being so pivoted to the pivoted member of the latch that when it is moved to closed position, it will lock the hook member in retracted position.

This invention also consists in certain other features of construction and in the combination and arrangement of the several parts, to be hereinafter fully described, illustrated in the accompanying drawings and specifically 20 pointed out in the appended claims.

In describing my invention in detail, reference will be had to the accompanying drawings wherein like characters denote like or corresponding parts throughout the several 25 views, and in which:

Figure 1 is a view showing portion of a barrier and its frame, with the latch in locking position.

Figure 2 is a plan view of the latch.

Figure 3 is an enlarged view showing the latch in open position.

Figure 4 is a view of the lever member.

As shown in these views, the latch comprises the pivoted member 1 and the hook member 2, the member 1 having a slotted bent part 3 at its outer end which forms a guide for the shank of the member 2. Said part 1 is also formed with an offset central portion 4 which provides a recess for a plate 5 which 35 has one end pivoted to the offset part and its other end is pivoted to the inner end of the shank of part 2. This plate forms part of a lever 6 which has one end connected with an edge of the plate by the lateral loop 7 so that the lever extends parallel to and is 40 spaced from the plate 7 and the free end of the lever is provided with a lateral extension 8 which forms a handle. The lever, when

closed, will have its part 8 resting upon the free end of the pivoted part 1, with the shank 50 of part 2 passing between the lever and the part 1, as clearly shown in Figure 2.

As will be seen from Figure 3, when the lever is swung upwardly the plate 5 will be rotated on its pivot and thus move the hook 55 part 2 outwardly and upwardly so that the hook part can be readily moved into and out of the keeper member 9 on the frame A of the door or other barrier B. When the door is to be fastened, the lever is swung upwardly 60 to project the hook part 2 and then the latch is moved on its pivot 10 to place the hook part into the keeper. Then the lever is swung downwardly, which will contract the part 2 and thus cause the recess 11 at the junction 65 of the beak of the hook with the shank, to engage a part of the staple of the keeper and thus the latch will be firmly held in locking position and as the lever is moved to the limit of its downward movement, the end 70 of the plate 5, which is pivoted to the part 2, will move upwardly beyond the pivotal point of the plate to the member 1 and thus the parts will be locked in position and cannot be moved until the lever is swung upwardly again. The inward movement of the part 2 will tend to pull the door toward its 75 frame and thus hold the door in tightly closed position.

It is thought from the foregoing description that the advantages and novel features of my invention will be readily apparent.

I desire it to be understood that I may make changes in the construction and in the combination and arrangement of the several parts, 85 provided that such changes fall within the scope of the appended claims.

What I claim is:—

1. A latch of the class described comprising a pivoted part and a hook part, a guide 90 on the pivoted part through which the other part passes, a plate pivoted to the pivoted part and having one end pivoted to the inner end of the hook part and a lever connected with the plate for turning the same on its 95 pivot to project and retract the hook part

and also to raise and lower the hook part as it is projected and retracted.

2. A latch comprising a pair of parts, a guide on one part through which the other part passes, a plate having one end pivoted to one part and its other end pivoted to the inner end of the second part, a lever having a lateral loop at one end which is connected with an edge of the plate and the other end

of the lever having a lateral extension for 10 engaging an edge of the first mentioned part to limit the downward movement of the lever, said lever, when in its lowermost position, moving the plate beyond dead center to lock the parts in closed position. 15

In testimony whereof I affix my signature.

MAURICE A. ESTABROOKS.
